UNITED STATES PATENT OFFICE

LAYMAN M. STERNBERGH, OF OCEAN GROVE, NEW JERSEY

SPLASH GUARD AND TILE FOR FORMING THE SAME

Application filed April 9, 1930. Serial No. 442,914.

This invention relates to a shower bath construction and more particularly to a splash guard and tile by means of which the guard may be constructed.

At the present time when building a shower bath of the alcove type or of the type in which the shower is an auxiliary to a tub, it is customary to provide a curtain in order to prevent water discharged by an overhead nozzle from spraying outwardly onto the floor of a room. The lower end portion of the curtain either extends downwardly into the tub or back of a ledge across the front of an alcove in order to prevent water dripping from the curtain onto the floor but no provision is made to prevent water from striking the walls and splashing past side edges of the curtain. This often causes puddles of water to accumulate on the floor even if care is taken to properly dispose the lower end of the curtain.

Therefore, one object of the invention is to provide a splash guard which by extending vertically and overlapping the inner surfaces of the curtain along sides thereof will serve very effectively to prevent water from splashing past side edges of the curtain.

It also very often happens that a person will be badly injured due to slipping and falling when stepping from a tub and, therefore, another object of the invention is to so form the splash guards for the side edges of the curtain that they may also serve as hand-holds adapted to be easily grasped and thereby prevent danger of slipping.

Most bath rooms have the walls faced with tiles in order to impart a good appearance and also prevent damage by water and allow the room to be easily and thoroughly cleaned. It is, therefore, another object of the invention to provide a tile adapted to be applied to a wall in the usual manner and having such construction that when a suitable number of these tiles are set in place one above another they serve to form the improved splash guard.

The invention is illustrated in the accompanying drawings, wherein

Figure 1 is a perspective view showing the

improved splash guards erected in operative relation to a tub and shower curtain,

Fig. 2 is a top plan view of one of the tiles from which the splash guards are formed,

Fig. 3 is a fragmentary sectional view taken through adjoining tiles of a guard on the line 3-3 of Fig. 2,

Fig. 4 is a sectional view showing a shower bath of the alcove type provided with the improved splash guards,

Fig. 5 is a top plan view of one of the tiles forming the splash guards shown in Fig. 4, and

Fig. 6 is a view in elevation showing adjoining portions of a splash guard and floor strip formed in accordance with this invention.

In Fig. 1, there has shown a tub 1 of a conventional construction extending between oppositely disposed walls of a bath room. A shower nozzle 2 projects from one wall over the tub and there has also been provided a shower curtain 3 suspended from a rod 4 so that it may be slid along the rod from the folded position illustrated to an extended position for use in which it extends the full length of the rod with its lower end projecting downwardly a short distance within the tub. This curtain serves to prevent water easily splashing outwardly from the shower and since the lower end of the curtain extends into the tub water dripping off the curtain passes into the tub instead of dripping upon the floor. It has, however, been found that water will often splash against the walls of the room at the ends of the tub and pass between the walls and side edges of the curtain. This water runs downwardly along the walls and accumulates in puddles upon the floor. In order to prevent water from passing between the wall and side edges of the shower curtain, I have provided splash guards in the form of ribs 5 which extend vertically at the ends of the tub and project from the walls a sufficient distance to overlap the curtain along its sides. By this arrangement the ribs or guards will serve very effectively to prevent water from splashing outwardly between the curtain and the wall. Any water at

tempting to pass outwardly strikes the inner side faces of the ribs and flows downwardly along the rods until it reaches the tub and instead of forming puddles upon the floor this water will flow into the tub.

Each of the splash guards or ribs 5 consists of a number of tiles 6. These tiles are applied to the wall and secured in the usual manner in which tiles are mounted and each tile consists of a base or body portion 7 which may be square, oblong or of any other desired shape. An arm 8 projects outwardly from the base or body portion 7 of the tile to form a section of the completed rib or splash guard, and by referring to Figure 2 it will be seen that the arm tapers outwardly for a portion of its depth and is then of an even thickness for a short distance and terminates in an enlarged head or bead 9. By this arrangement the tiles forming the guard may be set in place against a wall one above another and their beads or heads will form a rail or grip 10 adapted to be grasped so that a person may step from the tub onto the floor of the room without danger of slipping and being injured by a fall. The upper and lower edge faces of the tiles are recessed, as shown at 11, thereby forming pockets adapted to be filled with cement placed between the tiles as a binder, as shown at 12 in Figure 3. By this arrangement the tiles forming the guard will be firmly braced against transverse movement and they will not be liable to be wrenched loose by a person grasping a guard and using the same as a hand rail to prevent slipping.

In Figure 4, there has been shown a shower bath of the alcove type. This shower bath which is indicated in general by the numeral 13 has opposed walls 14 leading from the walls 15 of the room and at the intersection of the walls 14 and 15 it is customary to use corner tiles having curved side flanges in order to form rounded corners and impart a good appearance. The corner tiles 16 are similar in construction to the tiles 6, except that they have side flanges or extensions 17. Arms 18 corresponding to the arms 8 project from the body portions 19 of these tiles and each arm terminates in an enlarged bead or head 20. It will thus be seen that when these tiles are set in place they will form guard rails 21 corresponding to the guard rails 5 and projecting from the walls 14 a sufficient distance to overlap the curtain 22 and prevent water from splashing outwardly between the curtain and walls of the alcove. It will be obvious that the water will be entirely confined within the alcove shower bath as the guards 21 overlap side portions of the curtain and the lower end of the curtain extends back of the usual ledge. Tiles, such as shown in Figures 4 and 5, may be used in place of the tiles 6 in

case the tub is built into an alcove or recess instead of at one end or side of a room.

In Figure 6, there has been shown another modified construction. In this form tiles 24 which are similar in construction to the tiles 6 are set into a floor in order to form an upstanding ledge extending across the front of an alcove shower and taking the place of the shoulder or ledge and the vertically extending splash guards are formed by tiles 25 which may be constructed either as shown in Figure 2 or as shown in Figure 5. In order to join the lower end of each vertical splash guard with the adjacent end of the floor ledge, there is employed a tile 26 formed substantially the same as the tiles 24 and 25, except that it is substantially triangular in shape in order to fit into a corner and has its bead 27 arcuate instead of straight so that it merges into the beads of the tiles 24 and 25. By this arrangement both the vertically extending splash guards and a horizontally extending guard to overlap the lower end of a shower curtain may be formed of tiles. Certain of the tiles from which the guards are formed may be provided with spurs 28 adapted to engage through eyes 29 at the sides of the curtain and releasably hold the curtain in place.

Having thus described the invention, I claim:

1. The combination with a shower structure including a chamber having a side wall, and a splash curtain, of a vertically extending rib projecting from the wall and being of sufficient depth to overlap a side portion of the curtain and having its outer portion formed with a hand grip.

2. The combination with a shower structure including a chamber having a side wall, and a splash curtain, of a plurality of tiles applied to said wall one above another, said tiles having wall engaging portions and portions extending outwardly therefrom between their side edges and forming arms decreasing in thickness towards their free ends, said arms cooperating to form a rib projecting from the wall and of sufficient depth to overlap a side portion of the curtain and constitute a splash guard.

3. The combination with a shower structure including a chamber having a side wall, and a splash curtain, of a plurality of tiles applied to said wall one above another, said tiles each having an arm extending outwardly therefrom and formed with a head at its outer end, the arms of said tiles cooperating to form a rib constituting a splash guard adapted to overlap a side portion of the curtain, and the heads forming a hand grip along the outer edge of the rib.

4. In a shower structure, a chamber having opposed side walls, a water-retaining wall extending across the floor of the cham-

ber between the side walls, a splash curtain extending between the side walls with the water-retaining wall overlapping the outer face of its lower portion, and ribs extending vertically upon the side walls and projecting therefrom to form splash guards adapted to overlap the outer face of the curtain along side portions thereof.

5. In a shower structure, a chamber having opposed side walls, a water-retaining wall extending across the floor of the chamber between the side walls, a splash curtain extending between the side walls with the water-retaining wall overlapping the outer face of its lower portion, and ribs extending vertically upon the side walls constituting splash guards to overlap said curtain along opposite sides thereof, the ribs having their free edge portions thickened transversely to 20 form hand grips.

6. In a shower bath construction, a splash guard consisting of a plurality of tiles disposed one against another and each being substantially T-shaped and having a wall 25 engaging portion and a portion extended outwardly therefrom intermediate its side edges to form an arm, the arms of said tiles contacting in end to end engagement with each other and cooperating to form the 30 guard.

7. In a shower bath construction, a splash guard consisting of a plurality of tiles disposed one against another and each having a portion extended outwardly to form an 35 arm terminating in a thickened portion forming a bead, the arms cooperating to form a rib and the beads forming a hand grip along the rib.

8. A splash guard forming tile comprising 40 a body, and an arm extending outwardly therefrom and formed with a bead along its free end.

In testimony whereof I affix my signature.
LAYMAN M. STERNBERGH. [L. s.]
